Robert H. Crowle, Berwyn, and Charles E. Jones,
Chicago, Ill., assignors to The Harmony Com-
pany, Chicago, Ill., a corporation of Illinois

Application May 19, 1950, Serial No. 10,044

Term of patent 7 years

(Cl. D56—1)

To all whom it may concern:

Be it known that we, Charles E. Jones and Robert H. Crowle, citizens of the United States and residents of Chicago and Berwyn, respectively, in the county of Cook and State of Illinois, have invented a new, original, and ornamental Design for a Ukulele, of which the following is a specification, reference being had to the accompanying drawing, forming a part thereof.

Fig. 1 is a perspective view of a ukulele showing our new design;

Fig. 2 is a side elevation of the same drawn to a reduced scale.

We claim:

The ornamental design for a ukulele substantially as shown and described.

ROBERT H. CROWLE.
CHARLES E. JONES.
